UNITED STATES PATENT OFFICE.

CLAUDE TACHON, OF CHARLIEU, LOIRE, FRANCE, ASSIGNOR, BY DIRECT AND MESNE ASSIGNMENTS, TO HERMAN SPAHN, OF NEW YORK, N. Y., AND EDOUARD G. LANDRU, OF UNION, NEW JERSEY.

MACHINE FOR FINISHING AND POLISHING TEXTILE FABRICS.

SPECIFICATION forming part of Letters Patent No. 376,994, dated January 24, 1888.

Application filed May 7, 1887. Serial No. 237,405. (No model.) Patented in France October 29, 1886, No. 179,384.

To all whom it may concern:

Be it known that I, CLAUDE TACHON, a citizen of the Republic of France, residing at Charlieu, Department of Loire, France, have 5 invented certain new and useful Improvements in Machines for Finishing and Polishing Textile Fabrics, (for which I obtained patent in France, No. 179,384, dated October 29, 1886,) of which the following is a specification.

10 In another application for Letters Patent filed simultaneously herewith under Serial No. 237,404 I have described and shown a machine for finishing and polishing textile fabrics, in which a series of rotating flexible blades are 15 caused to act on the surface of the goods transversely to the direction of motion of the goods.

In the machine for finishing and polishing textile fabrics forming the subject-matter of my present invention, the flexible polishing-20 blades are arranged and actuated to rub the goods longitudinally or in the direction of their movement as they are fed through the machine, said rubbing action being such as to smooth down the threads, remove all irregularities therefrom, and close up the interstices 25 between the weft and warp of the goods.

The flexible blades are attached in sets to shafts running in bearings on the main frame of the machine, the blades of each set being 30 so located on their respective shafts as to occupy different lateral positions relatively to the goods, so that as they are rotated and caused to act on the goods all parts thereof are uniformly submitted to an equal amount of 35 rubbing action.

To fully describe the construction and operation of the various parts of this improved finishing and polishing machine, I will now refer to the accompanying drawings, in which—

40 Figure 1, Sheet 1, is a plan view of the complete machine. Fig. 2, Sheet 2, is a side elevation of the same. Fig. 3, Sheet 3, is a rear elevation or view of the end of the machine at which the goods enter. Fig. 4, Sheet 4, is a 45 sectional elevation taken on the line $\alpha\alpha$, Fig. 1. Fig. 5, Sheet 3, is an enlarged front view of a part of one of the polishing-shafts and flexible blades. Fig. 6, Sheet 3, is a plan view, and Fig. 7, Sheet 3, is a transverse section of 50 the same.

The main frame a is rectangular in form, and in the upper part thereof, supported on the leveling-screws b , b' , is the yielding bed, of the same construction as the bed described and claimed in my before-mentioned application, 55 and consisting of the box b , elastic air-chamber c , provided with the inlet-pipe c' and pressure-regulating cock c'' , the cloth covering d , and strips of leather e , e' . These strips of leather are secured to the edges of the box b , 60 so as to lie at an angle to the goods as shown at Fig. 1, the object of which will be herein-after explained.

The shafts ff , which carry the flexible blades g , g' , rotate in bearings on the tops of the sides 65 of the main frame a , and they are all driven in the same direction by means of bevel-pinions h , h' , secured to the shaft i , placed longitudinally in bearings projecting from the side of the frame, meshing into the bevel-wheels h' , 70 h'' , secured to the ends of the shafts ff , adjacent to the shaft i . The other ends of the shafts ff are provided with similar bevel-wheels, h^2 , h^2' . This permits of the shafts ff being reversed 75 in position in their bearings, so that the other sides of the flexible blades g , g' will strike the goods j , thus providing means for counteracting any set imparted to the blades by prolonged use in either direction.

The shaft i is driven by means of the bevel- 80 pinion k , which is secured to the driving-pulley k' , and which meshes into the bevel-wheel k^2 , secured to the rear end of the shaft i . Each of the shafts f has square grooves formed longitudinally therein on opposite sides thereof, 85 and the flexible rubbing-blades g , g' are secured to the shafts by means of screws passing through them and through washers or plates g , g' into the radial sides of the grooves, as shown at Figs. 5, 6, and 7, in which views the washers g , g' are tapering, so that the blades g , g' are oblique to the axes of the shafts ff , which position it is desirable they should occupy in treating some kinds of goods. In the main views of the drawings the blades are in line with the axes of the shafts, so that their ends strike 90 squarely on the goods.

The flexible blades are each composed of a central spring-tempered steel plate and reinforcing side springs.

As before stated, all of the blades *g g* rotate in the same direction, but they are so set as not to strike or act on the goods *j* together. There are six sets of blades shown in the drawings; but this number may be varied as desired. The first and fourth, second and fifth, and the third and sixth sets occupy similar angular positions, the angular differences between them being such that during a short interval of time all of the blades are clear of the goods, thus allowing the goods to regain the normal tension due to the feeding device should it be altered by the action of the blades on the goods.

15 It will be observed by referring to Fig. 1 that the blades *g g* are arranged on the shafts *ff* so that no two blades on different shafts are directly in line with one another, and it is necessary that the edges of the blades shall be 20 opposed by or work on a uniform bed-surface, for which reason the leather straps *ee* are placed at an angle on the bed, so as to be directly under the blades.

It is found preferable to have the blades act 25 on the goods in the direction in which they are drawn through the machine; and, to prevent the goods being drawn forward faster than the feeding device is set to act, the roller *l*, on which the goods are placed, is provided with a brake 30 or retarding device, consisting of a strap, *m*, passing over the roller *l*, a lever, *n*, to one end of which the strap *m* is fastened, and the weight *o*, placed on the other end of the lever *n*. This weight *o* is adjustable on the lever *n*, so that 35 the friction between the strap *m* and roller *l* may be varied at pleasure. The rear and front guides, *p* and *q*, respectively, vary in height throughout their lengths in a similar manner to and for the same object as the corresponding 40 guides in my before-mentioned application; so it is here unnecessary to further enter into their construction. The goods, after passing over the front guide, *q*, are wound up on the roller *r*, which has a continuous rotary motion 45 imparted to it by means of the worm-wheel *r'* on its end, the worm *s* working therein and secured to the shaft of the conical pulley *s'*, the reverse conical pulley *t*, driven by a gear-wheel on the end of the shaft *i*, and the connecting-belt 50 *t'*. This belt *t'* is controlled by the shifter *u*, actuated by the screw *u'*, provided with the hand-wheel *u''*, by the manipulation of which the belt *t'* is shifted along the conical pulleys, and the speed of the winding-up roller *r* varied at 55 pleasure.

The particular construction of the elastic bed *b c d e* and the guides *p q* shown in the drawings forms no part of the present invention, being described and claimed in my before-mentioned application.

Having now described my invention, what I claim, and desire to secure by Letters Patent, is—

1. In a machine for finishing and polishing textile fabrics, in combination, an elastic bed, feeding mechanism for drawing the goods over the bed, several series of flexible blades rotated in one direction, arranged to act longitudinally on the goods and set in different angular positions, and devices for imparting a continuous rotary motion to the flexible blades, substantially as set forth.

2. In a machine for finishing and polishing textile fabrics, in combination, an elastic bed, feeding mechanism for drawing the goods over the bed, several series of flexible blades rotated in one direction and arranged to act longitudinally on the goods in the direction in which the goods travel over the bed, devices for imparting a continuous rotary motion to the flexible blades, and a brake or retarding device acting on the roller holding the goods, substantially as and for the purpose set forth.

3. In a machine for finishing and polishing textile fabrics, in combination, feeding mechanism for drawing the goods through the machine, transversely-arranged shafts, devices for continuously rotating the shafts, flexible blades secured to the transverse shafts so as to occupy different lateral positions in relation to the goods, and an elastic bed provided with strips of leather obliquely arranged thereon, between which and the flexible blades the goods are drawn, substantially as and for the purpose set forth.

4. In combination, the side shaft, *i*, provided with bevel-pinions *h h*, the shafts *ff*, provided with bevel-wheels *h' h'* on one of their ends and similar bevel-wheels, *h'' h''*, on their other ends, the flexible rubbing-blades *g g*, secured to the shafts *ff*, and the elastic bed *c d e*, substantially as set forth.

In witness whereof I have hereunto set my hand this 23d day of March, A. D. 1887.

CLAUDE TACHON.
